UNITED STATES PATENT OFFICE.

FELIX P. PROSSEN, OF JERSEY CITY, NEW JERSEY.

CARBURETER.

1,201,759.

Specification of Letters Patent. Patented Oct. 17, 1916.

Application filed July 14, 1914. Serial No. 850,848.

To all whom it may concern:

Be it known that I, FELIX P. PROSSEN, a citizen of the United States, residing at Jersey City, in the county of Hudson and State of New Jersey, have invented a certain new and useful Improvement in Carbureters, of which the following is a specification.

This invention relates to carbureters, and it consists in certain novel construction hereinafter specified and including a tube spaced from the walls of a casing, a stationary shell within the tube, and an inner shell movable vertically by suction against an air cushion formed between the shells, the necessary provision being made for air and fuel supply.

I will first describe my improvement in detail and then point out the novel features in the claims.

In the accompanying drawings Figure 1 is a vertical sectional view of a carbureter; Fig. 2 is another vertical section of the carbureter illustrated in Fig. 1; and Fig. 3 is a sectional view thereof taken through the plane of the dotted line 3—3, Fig. 2.

Similar letters of reference designate corresponding parts in all the figures.

A designates a shell.

B designates a neck, the upper end of which is shown as provided with flanges, as b, having suitable screw threaded openings, as b', to enable the carbureter to be fastened to the motor manifold. A flange, as b², is shown as provided at the lower end of the neck B, and within the neck B a throttle valve C is shown as arranged.

D designates a tube shown as provided with an upper flange, as d, and a lower flange, as d'. This tube D is shown as also provided near its upper end with ports or openings d², and below these ports or openings other ports or openings, as d³, are shown as arranged. The flanges d and d' hold the shell A and tube D in such position relatively to each other that a chamber E is formed between the shell A and tube D.

F designates a collar shown as screw threaded and as engaging with a screw threaded portion d⁴ of the tube D. This collar F is shown as extending over the flange b² and as holding the neck B and tube D together. The collar F serves as a coupling to connect the body of the carbureter and neck B and so holds the carbureter body and neck B together that the body may be moved independently of said neck.

G designates a shell shown as arranged within the tube D. This shell G is shown as provided near its lower end with ports or openings, as g. These ports or openings g are shown as tapered in their sides and as being wider at their bottoms than at their tops. The upper end of the shell G is shown as provided with an inwardly and downwardly turned flange g', and the space 65 formed by this flange g' provides an air cushion, or air dash pot as O. The shell G and tube D may be held in position by means of a screw, as g².

A shell, as H, is shown as arranged with 70 in the shell G. Ports or openings h are shown as provided in the lower end of this shell H, and the ports or openings h are shown as tapered in their sides and as being wider at their tops than at their bottoms. 75 A slot or groove, as h', may be provided in the side of the shell H and a projection, as g³, on the interior of the shell G may fit into this slot or groove h' preventing the rotation of shell H and guiding the latter. 80

I designates a tube affixed to the shell H. The interior of this tube I is shown as tapered. On the tube I a spider cap J is shown as arranged. From this cap J there is shown as depending a needle, as K, provided with a ball or head k, which permits the needle K to be held in a collar, as j, shown as fastened to a screw threaded stud j', the upper end of which is shown as 85 screwed into the cap J. A nut, as j², is 90 shown as provided for locking the stud j' in position, when set. The stud j' may be provided with a slot, as j³, into which a screw driver may be inserted to move the stud j', and, with it, the needle K, upward 95 or downward, as desired.

L designates an inlet through which hydrocarbon may be introduced to a nozzle, as M, from a suitable float chamber.

N designates a horn which acts as an air inlet. This horn N is shown as provided with ports or openings, as n, through which air may be admitted to the horn N, and a valve, as n', is shown as arranged in the horn N. I prefer that air introduced into 100 the horn N be heated, but if, for any reason, it be desired to admit cold air to the horn N, such cold air may be admitted through the ports or openings n.

I will now describe the operation of the 110 carbureter illustrated in the drawings, Fig. 1 illustrating a carbureter embodying my

improvement when the same is practically closed, and Fig. 2 illustrating the same carbureter when "wide open."

At the outset it may be premised that when the carbureter is in a state of rest the ports d^2 , g and h are not in communication, and that when the ports h are closed the smallest diameter of the tube I is on a line with the upper end of the nozzle M. The pressure of air introduced to the interior of the shell H tends to cause the shell H to move upward but this upward tendency is opposed by the weight of the shell H and tube I and by the air confined in the space O. When the pressure of air introduced through the horn N is sufficient to overcome the weight of the shell H and tube I and the air confined in the space O the shell H will move upward. The upward movement of the shell H carries upward the ports h , and when the ports h have moved sufficiently far upward they are brought into communication with the ports g and mixed air and hydrocarbon passing through the ports h and g enters the chamber E through the ports or openings d^2 . The mixed air and hydrocarbon introduced into the chamber E finds outlet in the ports d^2 and from the ports d^2 passes into the neck B where it combines with the mixture passing through cap J from tube I. The valve C will, of course, control the discharge from the neck B.

In the drawings I have shown a space, as Q, which may be loaded, as desired, to increase the weight of the shell H.

The upward movement of the shell H will necessarily cause an upward movement of the tube I, and the upward movement of the tube I will raise the needle K. The air cushion or air dash pot O will, of course, tend to check sudden movements of the shell H. It will of course be understood that in its movements upward and downward the shell H is guided by the slot or groove h' and projection g^2 , and that the tube D and shell G are held in proper position relatively to each other by the screw g^2 .

The lower reduced portion of the needle K is shown as cylindrical in shape. Thereby, while a rising movement of the needle K opens the nozzle M yet, when the lower tapered portion of the needle K has reached the level of the upper end of the nozzle M, further upward movement of the needle K does not open the nozzle M farther, but when the lower tapered portion of the needle K has reached the upper end of the nozzle M the lower reduced cylindrical portion of the needle K acts as a guide for the needle K in further movement of said needle K.

The shell H forms a carbureting chamber in which air and hydrocarbon are mixed and while the tendency of the mixed air and hydrocarbon is to force itself upward

through the tube I, yet, when the upward movement of the shell H brings the ports h and g into communication so that said ports form a passage between the shell H and chamber E mixed air and hydrocarbon will flow from the shell H into the chamber E and this mixed air and hydrocarbon passes through the ports or openings d^2 and mixes with the mixed air and hydrocarbon which has passed through the tube I.

What I claim as my invention and desire to secure by Letters Patent is:

1. In a carbureter, a casing, a tube therein spaced from the inner walls of the casing to form a chamber, said tube having ports communicating with the chamber, a shell within the tube having ports registering with certain of the ports of the tube, an inner shell movable vertically by suction against an air cushion between portions of the side walls of the shells, and having ports registering at times with the ports of the first shell, means for introducing air into the chamber surrounding said tube and means for introducing liquid fuel into the inner shell.

2. In a carbureter, a casing, a tube therein spaced from the inner walls of the casing to form a chamber, said tube having ports communicating with the chamber, a shell within the tube having ports registering with certain of the ports of the tube, a weighted inner shell movable vertically by suction against an air cushion between portions of the side walls of the shells, and having ports registering at times with the ports of the first shell, means for introducing air into the chamber surrounding said tube, and means for introducing liquid fuel into the inner shell, said inner shell carrying a valve member projecting from the top thereof.

3. In a carbureter, a casing, a tube therein spaced from the inner walls of the casing to form a chamber, said tube having ports communicating with the chamber, a shell within the tube having ports registering with certain of the ports of the tube, an inner shell movable vertically by suction against an air cushion between portions of the side walls of the shells, and having ports registering at times with the ports of the first shell, means for introducing air into the chamber surrounding said tube, means for introducing liquid fuel into the inner shell, a cap for the inner shell having openings therein, a socket member carried by the cap, a tapered valve member having a cylindrical lower portion, said member being held within the socket, and means projecting through the cap for adjusting said member.

4. In a carbureter, a casing, a tube therein spaced from the inner walls of the casing and having ports communicating with the upper and lower portions of the chamber thus formed, a shell within the tube having a flanged portion and having ports register-

ing with certain of the ports of the tube, and an inner shell having a reduced portion, movable vertically by suction against an air cushion between the shells and having ports 5 registering at times with the ports of the first shell, means for introducing air, means for introducing liquid fuel to the lower portion of the inner shell, the air and liquid fuel passing through the inner shell and combining with the air passing through the registering ports and through the chamber between the casing and tube.

5. In a carbureter, a casing comprising a neck portion and a body portion rotatable 15 with reference to the neck, a tube therein spaced from the inner walls of the casing and having ports communicating with the upper and lower portions of the chamber thus formed, a shell within the tube having 20 a flanged portion and having ports registering with certain of the ports of the tube, and an inner shell having a reduced portion movable vertically by suction against an air cushion between the shells and having ports 25 registering at times with the ports of the first shell, means for introducing air, means for introducing liquid fuel to the lower portion of the inner shell, the air and liquid fuel passing through the inner shell and combining with the air passing through the 30 registering ports and through the chamber between the casing and tube.

6. In a carbureter, a casing comprising a neck portion and a body portion rotatable 35 with reference to the neck, a tube therein spaced from the inner walls of the casing and having ports communicating with the upper and lower portions of the chamber

thus formed, a shell within the tube having a flanged portion and having ports registering with certain of the ports of the tube, and an inner shell having a reduced portion movable vertically by suction against an air cushion between the shells and having ports 40 registering at times with the ports of the first shell, means for introducing air, means for introducing liquid fuel to the lower portion of the inner shell, the air and liquid fuel passing through the inner shell and combining with the air passing through the 45 registering ports and through the chamber between the casing and tube, one of said shells being grooved and a projection on the other of said shells engaging the groove.

7. In a carbureter, a casing, a tube therein spaced from the inner walls of the casing and having ports communicating with said space, a shell within the tube having ports with inclined walls registering with certain of the ports of the tube, an inner shell movable vertically by suction against an air cushion between portions of the side walls of the shells, and having ports with walls inclined oppositely to those of the first shell and communicating at times therewith, a 60 casing having a liquid fuel inlet, a valve member controlling the inlet and mounted in the inner shell, said inner shell having ports in its upper portion and having a chamber for receiving material for balancing the shell.
